SWIM FIN

Everett A. Brunner, 3807 N. Merced, Baldwin Park, Calif.

Filed Sept. 14, 1964, Ser. No. 81,744

Term of patent 14 years

(Cl. D71—1)

FIG. 1

FIG. 2

FIG. 3

FIG. 4

FIGURE 1 is a perspective view of a swim fin, showing my new design;

FIGURE 2 is a plan view thereof;

FIGURE 3 is a side elevational view thereof; and

FIGURE 4 is a bottom view thereof.

The dominant features of my design reside in the portions shown in full lines.

I claim:

The ornamental design for a swim fin, as shown and described.
